UNITED STATES PATENT OFFICE

114,609

DESIGN FOR A STOCKING

Samuel I. Burd, Philadelphia, Pa.

Application January 19, 1939, Serial No. 82,441

Term of patent 3½ years

To all whom it may concern:

Be it known that I, Samuel I. Burd, a citizen of the United States and a resident of Philadelphia, county of Philadelphia, State of Pennsylvania, have invented a new, original, and ornamental Design for a Stocking, of which the following is a specification, reference being had to the accompanying drawings, forming a part thereof, wherein:

Figure 1 is a view of a stocking showing my new design in side elevation; and

Figure 2 is a top plan view of the toe portion of the stocking.

Fig. 3 is an enlarged top plan view of the toe portion of the stocking.

The characteristic features of the design reside in a knitted stocking having a zone in its toe portion formed with closely spaced, irregularly shaped openings forming a repetitive design in which the unit of design consists of a relatively large open-

ing and an adjacent pair of smaller openings, said openings being disposed on a line biased relatively to the direction of the wales in the foot of the stocking, providing a fabric design of the stocking toe in which said units of design form parallel lines extending diagonally in a single direction with respect to the wales and in which said large openings form parallel lines extending lengthwise of the wales, said units being each bounded by closely knitted fabric and providing lines of closely knitted fabric extending diagonally relatively to the wales, said zone having a relatively narrow transverse strip of such closely knit fabric constituting a border for said zone and transposed between the toe portion and the instep of the stocking.

I claim:

The ornamental design for a stocking, as shown and described.

SAMUEL I. BURD.
